Primary Examiner — Derrick E Holland*Assistant Examiner* — Andrew Kerr(74) *Attorney, Agent, or Firm* — Jonathan E. Grant; Grant Patent Services(57) **CLAIM**

The ornamental design for a spigot, as shown and described.

DESCRIPTION

FIG. 1—is a bottom perspective view of a spigot, showing my new design;

FIG. 2—is a rear view thereof;

FIG. 3—is a front view thereof;

FIG. 4—is a first side view thereof;

FIG. 5—is a second side view thereof;

FIG. 6—is a bottom view thereof; and,

FIG. 7 is a top view thereof.

The broken lines in the drawing views represent environmental structure and form no part of the claimed design.
